FIG. 2

FIG. 1

INVENTOR
EDWIN MOSTHAF
BY *Jas. P. Falvey*
ATTORNEY

UNITED STATES PATENT OFFICE

105,538

DESIGN FOR A SPARK PLUG GAPPING TOOL

Edwin Mosthaf, Toledo, Ohio, assignor to The Electric Auto-Lite Company, Toledo, Ohio, a corporation of Ohio

Application March 17, 1937, Serial No. 68,227

Term of patent 14 years

To all whom it may concern:

Be it known that I, Edwin Mosthaf, a citizen of the United States, residing at Toledo, in the county of Lucas and State of Ohio, have invented a new, original, and ornamental Design for a Spark Plug Gapping Tool, of which the following is a specification, reference being had to the accompanying drawing, forming a part thereof.

Figure 1 of the drawing is a plan view of a spark plug gapping tool showing my new design.

Figure 2 is a sectional elevation taken along the lines 2—2 of Figure 1.

I claim:

The ornamental design for a spark plug gapping tool as shown.

EDWIN MOSTHAF.
